UNITED STATES PATENT OFFICE.

HENRY MCGAHEY, OF CAMBRIDGE, MASSACHUSETTS.

SASH-FASTENER.

SPECIFICATION forming part of Letters Patent No. 643,195, dated February 13, 1900.

Application filed April 22, 1899. Serial No. 714,013. (No model.)

To all whom it may concern:

Be it known that I, HENRY MCGAHEY, of Cambridge, county of Middlesex, State of Massachusetts, have invented an Improvement in 5 Sash-Fasteners, of which the following description, in connection with the accompanying drawings, is a specification, like letters and numerals on the drawings representing like parts.

10 This invention has for its object the production of a novel sash fastening or locking device adapted to retain a sash in any desired position, said device preventing any farther opening of the sash, but permitting it to be closed 15 and locked automatically.

The device is under the control of an actuator device having preferably a detachable key.

Figure 1 shows a window-frame with an upper and a lower sash both closed. Fig. 2 is an enlarged detail broken out, showing one edge of the two sash, part of the window-frame, and the fasteners, the full lines showing the fasteners in operative positions, the dotted lines showing the fastener disengaged. Fig. 3 is a view of the parts shown in Fig. 2 looking from the right. Fig. 4 shows a face view of the key.

The window-frame A may be of any usual 30 shape. The top sash B and bottom sash C may be of any usual shape or style, I, in accordance with my invention, adding to the edge of the sash like engaging plates a, having a series of holes a', separated one from 35 another, according to the various locking-stations desired for the sash.

To the inner wall of the side of the window-frame I attach, by screws b' or in any other suitable manner, one end of like fasteners, 40 (shown as spring-fingers b² b³), each having at one end a prong, as b⁴ b⁵, said prongs being beveled at their ends, said bevels, however, when the fingers are applied to the casing, standing oppositely, as shown in full and dotted lines, Fig. 2, so that the bevel of the prong coöperating with the top sash is presented at the lower side of the prong, while the bevel of the finger coöperating with the bottom sash is beveled at its upper side. These fingers 45 are located in the runway or weight-box of the casing or frame, and their free ends

overlap, the finger connected with the casing and coöperating with the upper sash being extended upwardly to a point above that occupied by the under edge of the top sash 55 when closed, while the finger coöperating with the bottom sash is extended downwardly, its prong terminating at a point below the position occupied by the bottom sash when fully closed. Each prong stands in a like hole a² 60 of the casing. Between the free ends of these fingers and the casing I have applied a key or actuating device c, (shown as a crank,) sustained at one end in a suitable stand 2 and at its other or outer end in a part of the casing 65 A, the crank crossing both fingers near their pronged ends, the outer end of the crank being shown as made square or of other shape than round in cross-section to enable a key d to be applied to the said end to turn the crank. 70

The drawings show the two sashes locked and neither can be moved.

To open the window or move either sash, the operator will apply the key and turn the actuating device into its dotted-line position, 75 Fig. 2, operating both fingers and withdrawing both prongs from the locking-holes of the two sashes. In this condition either or both sashes may be moved, raised, or lowered, and when in the desired position the crank 80 may be again put in its full-line position, and a slight movement of either of the windows which was moved will cause the point of the prong to enter the hole a' nearest to it and lock the sash in position. Let it be supposed 85 that the bottom sash has been lifted and the top sash lowered and that a prong has entered one of the holes a' of the plates a. In this condition one may easily lower the bottom sash or raise the top sash to close them, 90 each sash being locked from station to station, such free movement of the said sash in the direction stated being permitted by the beveled ends of the prongs; but it will be understood that the bottom sash cannot be 95 raised nor can the top sash be lowered from any of their locked positions without using the key to turn the actuating device.

The fastener described affords a secure lock for the sash and yet permits a sash to be left 100 over night partially open without fear of its being further opened by a burglar, for the key

may be laid aside out of reach, so that it could not be turned by a hook or other device. The finger is held in place by a suitable eye *g*.

Instead of making holes *a'* entirely through 5 the plate *a* I may use deep notches.

Having fully described my invention, what I claim, and desire to secure by Letters Patent, is—

10 A sash-fastener consisting of two plates each having vertical openings and adapted to be secured to the upper and lower sashes, two spring-fingers secured at remote points to the window-frame in the runway or weight-box thereof and having inturned prongs at their 15 free ends adapted to pass through openings

in the window-frame and to engage in the openings in said plates, and the prongs having oppositely-beveled ends, and a shaft mounted upon the window-frame and provided with two cranks for engaging and operating the spring-fingers in unison to move the prongs out of the holes in said plates. 20

In testimony whereof I have signed my name to this specification in the presence of two subscribing witnesses.

HENRY MCGAHEY.
